UNITED STATES PATENT OFFICE.

JOHN CHOICE PRINTUP, OF ROME, GEORGIA.

SPARK-ARRESTER.

SPECIFICATION forming part of Letters Patent No. 288,488, dated November 13, 1883.

Application filed August 3, 1883. (No model.)

To all whom it may concern:

Be it known that I, JOHN CHOICE PRINTUP, of Rome, in the county of Floyd and State of Georgia, have invented a new and useful Improvement in Cone Spark-Arresters, of which the following is a full, clear, and exact description.

Reference is to be had to the accompanying drawings, forming part of this specification, 10 in which similar letters of reference indicate corresponding parts in both the figures.

Figure 1 is a sectional side elevation of my improvement, shown as applied to a locomotive smoke-stack. Fig. 2 is an under side view 15 of the same detached.

The object of this invention is to prevent sparks from escaping from the smoke-stacks of locomotive and other engines.

The invention consists of the combination 20 and arrangement of parts, substantially as hereinafter more fully set forth and claimed.

A represents the cylindrical lower part of a smoke-stack.

B is the flaring upper part or head, and C 25 is the tapered top or cap, which is hinged at one side to the said part B, and is secured at its other side by a spring-catch, D, or other suitable fastening. A sheet, E, of wire-gauze, can be secured to the upper edge of the cap C.

To the upper edge of the flaring head B of 30 the stack is secured by rivets or other suitable means the outer edge of a circular sheet-iron plate, F, through the center of which is formed a circular aperture, G.

H is a sheet-iron cone, which is inverted 35 and suspended at a little distance below the plate F by brackets I, attached to it and to the said plate F. The base of the cone H is made larger than the aperture G, and said

cone is made of such a size that the area of 40 the annular space surrounding the said cone shall be at least equal to the area of the cylindrical part A of the stack, so that the draft will not be obstructed. With this construction the sparks that pass up the stack will 45 strike against the inclined sides of the cone H, will be deflected against the outer part of the plate F and shell B, and will fall back into the lower part of the stack, whence they can be removed when desired.

If desired, the inner edge of the plate F 50 may be provided with a tapering or inwardly-inclined and downwardly-projecting ring-flange, J, for any sparks that may be carried inward after striking against the plate F to 55 strike against, and thus be prevented from passing out through the opening G.

Having thus described my invention, what I 60 claim as new, and desire to secure by Letters Patent, is—

In a spark-arrester, the combination, with 65 the head B, having the cap C hinged to the latter, and covered by a gauze-sheet, E, of the plate F, bolted to an inner annular flange at the upper flared end of the head B, and provided at its center with a deflector, J, with a lower convergent end, and the inverted cone H, suspended from the said plate by arms I, and having its upper flared end arranged a short distance below the deflector J, and having a greater diameter at said end than the lower end of the latter, as shown and described, and for the purpose set forth.

JOHN CHOICE PRINTUP.
